Primary Examiner — Jennifer L Rempfer*Assistant Examiner* — Michelle Marquart Christeon(57) **CLAIM**

The ornamental design for a red light therapy pad set, as shown and described.

DESCRIPTION

FIG. 1 is a top, front and left side perspective view of a red light therapy pad set showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The dotted lines shown on the red light therapy pad set depict stitching that form no part of the claimed design. The broken lines show the features of the red light therapy pad set that form no part of the claimed design. The dash-dot-dash broken lines define the boundary of enlarged views and form no part of the claimed design.
